PACKING RETAINER

Marvin H. Gorman, Corbin, Ky.

Application September 2, 1938, Serial No. 228,178

7 Claims. (Cl. 308—89)

This invention relates to the journal boxes and journals of railway cars and particularly to means for retaining packing therein.

The object of the invention is to provide a packing retainer which will hold the packing firmly in place within the journal box and not allow it to slip to one side of this journal as the car is in movement and which will keep constant pressure on the packing and thus keep the oil pressed to the top of the packing and feeding to the journal when the journal is running, thus eliminating the use of packing irons at each terminal to press the oil upward as at present.

Another object is to keep the packing in proper position and eliminate "waste grabs" and eliminate the robbing of packing from the journal box.

Another object of the invention is to provide a packing retainer which, when the car is running, will be kept in continual vibration so that the packing is alternately compressed and loosened, thus acting to pump oil up to the upper portion of the packing and against the journal instead of allowing the lubricant to accumulate in the bottom of the box.

The invention also has for an object to provide a device of this kind including means to effectively prevent robbing of the box in which the packing retainer is placed, said means also serving effectively as a shield to protect the packing against grit and other foreign matter which accumulates within the box during transit and which means also substantially eliminates the kicking or backing up of the packing against the brass.

My invention is illustrated in the accompanying drawings wherein:

Figure 1 is a vertical longitudinal section of a journal bearing with my packing holder in place.

Figure 2 is a side elevation of the packing holder.

Figure 3 is a top plan view thereof.

Figure 4 is a front elevation thereof.

Figure 5 is a sectional view taken transversely through a journal and through a retainer constructed in accordance with another embodiment of my invention, the box in brass being diametrically indicated by broken lines.

Figure 6 is a view in side elevation of the retainer as comprised in this second embodiment.

Figure 7 is a view in top plan of the device as illustrated in Figure 6.

Figure 8 is a view in front elevation of the structure as illustrated in Figure 6, with portions broken away.

Figure 9 is a fragmentary detailed sectional view taken substantially on the line 9—9 of Figure 7.

In the invention as embodied in Figures 1 to 4, it will be seen that my packing retainer is formed of a single piece of spring steel about $\frac{1}{4}$ " in diameter in actual practice. The strip of spring steel from which the retainer is made is bent at its middle to form an upward extension 10, then is extended laterally in a horizontal plane on opposite sides from said portion 10, as at 11, then extended upwardly and rearwardly, as at 12, then extended rearward at 13, bent to form a coiled spring 14, then extended longitudinally, as at 15, and then laterally bent at 16, the abutting ends of these laterally bent portions 16 being welded or otherwise connected to each other at 17.

It will be seen from Figure 1 that in the use of this device, the U-shaped portion formed of the legs 15 and the connecting elements 16 is disposed below the "brass" of the journal box with the portions 16 extending across the front end of the journal A. The lower legs 13 with their downwardly and inwardly inclined portions 11 and 12 are disposed to bear against the packing on each side of the journal and force this packing downward in the manner shown. The eye formed by the portion 10 permits a tool to be inserted to lift up the lower portion of the retainer. The coils 14, of course, act to resiliently connect the portions 15 with the portions 13 and urge the portions 13 downward into pressing engagement with the packing. In Figure 1, I have illustrated the journal box A of usual or suitable form within which the journal B operates, this journal box being provided with the journal brass C while the lower portion of the spring retainer rests against the packing D.

The legs 13 will be flattened somewhat and burred so that the retainer will hold better on the packing. The portions 12 should be bent downward, as shown in Figures 1 and 2 in order to fit over the packing at the front of the journal box and hold the packing back so as to prevent it from passing out of the forward end of the journal box, as it is very liable to do, unless means are taken to prevent this. In actual practice the arms 15 will terminate about $\frac{1}{4}$ " back of the upper end of the bends 12 while the cross-bar 16 should be disposed approximately 1" in front of the upper ends of the bends 12 when the parts are in the position shown in Figure 1. Obviously the length of the different portions will vary in order to fit different boxes. With

the parts shown in position in Figure 3, the cross bar 11 will be distanced from the cross bar 16 about 1½" and will bear against the front end of the box. The outwardly curved portions at 5 the extremities of the arms 15 accommodate the journal collar.

It will be seen that this retainer keeps the packing in proper position down and away from the bearing as well as pressing the oil to the top 10 of the packing. Furthermore, it entirely eliminates "waste grabs," that is, prevents the packing being moved up against the journal bearing by the movement of the journal. When the car is given a heavy application of brakes, the bearing 15 tilts and when it comes back into proper position on the journals, the journals catch the waste packing between the journal and the bearing and this is liable to cause a hot box if not seen and removed at once. This is entirely prevented in 20 my construction.

The retainer keeps a constant pressure on the packing and while the journal is running, the motion of the bearing on the spring keeps the oil within the packing pressed to the top of the 25 packing, feeding it to the journal and eliminating the use of packing irons at each terminal to press the oil upward, as at present necessary. This is due to the peculiar action of the retainer when the car is running. Under these circumstances, the journal B shifts back and forth within the box and this causes alternate compression and relief on or constant vibration of the spring arms. Thus a pumping action is 30 secured which alternately compresses the "dope" or packing and allows it to expand, thus securing a pumping action which keeps the lubricant pumped upward against the journal and prevents its sinking to the bottom of the box. This retainer also prevents the robbing of packing 35 from the journal box as it is almost impossible to pull the packing out of the box when the spring retainer is in place and the spring retainer cannot be lifted and the packing removed without a tool for that purpose. This is 40 due to the downwardly inclined portions 12 which extend downwardly and inwardly toward the middle of the box and to the cross bar 11. This cross bar extending as it does entirely across the packing, keeps the packing from working 45 forward and being forced out of the box and, inasmuch as the lower legs 13 are formed with prongs or teeth, the lower legs 13 with the cross bar 11 and the portions 12 so clamp the packing in place as to prevent the packing from being 50 pulled out by packing thieves except in small and useless shreds. The packing can only be removed bodily by removing the retainer and this cannot be done by hand. These upper and lower cross bars 16 and 11 permit the application 55 of a tool or "tongs" to the two cross bars, one jaw of the tongs passing through the eye 10, and thus permit the retainer to be compressed and pulled out and compressed, inserted and released. This retainer cannot be pulled out by 60 hand.

In ordinary practice, it is necessary that the "dope" or packing shall be tucked into the box by means of a packing knife every so often. This is done so as to force the packing down solidly 65 into the bottom of the box and pack it beneath the journal. This must be done every time the engine comes into the roundhouse and at more or less frequent intervals for every journal on every car. Inasmuch as this operation takes 70 about a minute for each box, a great deal of 75

time and money is spent in the course of the year in packing and re-packing and tucking in packing on the hundreds of thousands of cars in use. The necessity of tucking in the packing is entirely done away with by the use of this retainer due to the peculiar action of the retainer when the car is running and which, as before stated, causes a vibration of the device which alternately compresses and expands the packing and pumps the oil to the upper surface thereof 10 and against the journal.

In the invention as comprised in Figures 5 to 9, the general construction of the retainer is the same as in the first embodiment of the invention, except that the bottom legs 18 are preferably 15 substantially round in cross section from end to end and are free of prongs or teeth. The forward ends of the legs 18 are continued by the downwardly and inwardly disposed portions 19 arranged on substantially an S curve and which 20 are also in continuation with the intermediate cross bar 20 provided with the substantially circular positioned or upstanding extension or eye member 21. In this embodiment of my invention, each of the legs 18 has extending there- 25 along an inwardly directed plate 22 of desired width and which has its outer marginal portion provided with the knuckles 23 through which the leg 18 is freely disposed whereby the plate 22 can be swung up or down. The inner or free longi- 30 tudinal marginal portion of the plate 22 is formed with the downwardly disposed teeth 24.

The forward end portions of the plates 22 are continued by the inwardly and laterally disposed 35 extension plates or arms 25 disposed on a lengthwise or a slight downward curvature and these plates or arms 25 along their inner margins are also provided with the teeth 26.

The free end portion of one of the plates or arms 25 is provided with an opening 27 through 40 which is adapted to pass from above the locking tongue 28 extending out from the outer or free end of the second plate or arm 25. This locking tongue 28 has its outer portion slightly offset whereby is provided a shoulder or stop 29 to 45 limit the extent of insertion of the locking tongue 28 through the opening 27 and thus determine the extent of upward swinging movement of the plates 22 and 25 under the action of the compressed packing therebeneath. The rear portions 50 of each of the plates 22, and also the rear portions 30, extend beyond the adjacent coil spring 31 which boasts with a lower leg 13 and the associated upper leg 32.

The retainer as comprised in this second em- 55 bodiment of my invention is applied within the journal box in the same manner as has herein-before been set forth with respect to the invention as illustrated in Figures 1 to 4. In the initial insertion of this retainer within the journal box, the plates 22 and 25 are thrown upwardly to offer no hindrance or restriction to the desired application of the retainer. After proper placement of the retainer as a unit within the box, the plates or arms 25 are swung down- 60 wardly and inwardly with the locking tongue 28 contacting from above with the plate or arm 25 having the opening 27. This initial contact is in advance of the opening 27 and as the up- 65 permost plate or arm 25 is forced downwardly, the locking tongue 28 will of its own accord enter 70 and pass through the opening 27 and upon re- 75 lease of the applied pressure on these coacting plates or arms 25, the resultant expansion of the compressed packing will swing these plates 75

or arms 25 upwardly until such movement is prevented by the shoulder or stop 29, as hereinbefore mentioned.

The plates 22 and also the extension plates or arms 25 are of such widths as to constitute what may be termed top covers for the packing, the teeth 24 and 26 penetrating the packing from above closely adjacent to the journal, thus assuring the packing being effectively maintained in proper position. These plates 22 and extension plates or arms 25 also effectively protect the packing within the box against robbing as with the plates in their lowered or effective position it is impossible to remove the packing.

15 It will be further stated that these plates 22 and plates or arms 25 also materially increase the efficiency of the retainer in preventing "waste grab".

It is also to be particularly pointed out that 20 the rear extensions 30 of the plates 22 effectively prevent the rising of the packing in the rear portion of the box and particularly behind the coil springs 31. It is believed to be obvious that this second embodiment of my invention 25 also contains the same benefits and advantages and operates in the same manner as has hereinbefore been set forth in detail in connection with the embodiment of the invention, as comprised in Figures 1 to 4.

30 It is believed to be apparent that when the plates 22 and the plates or arms 25 are in their lowered or effective working position, the retainer cannot be removed from within the box but on the contrary before any such removal 35 can be accomplished the plates 22 and the extension plates or arms 25 must be raised to their inoperative position.

This application embodies a continuation in part of the invention as set forth in my application, Serial No. 155,137, filed July 22, 1937, the features of this former application as comprised in this present application being as illustrated by Figures 1 to 4 inclusive of the accompanying drawings.

45 What I claim is:

1. A packing retainer for journal boxes formed of a single length of spring material bent to form a lower cross bar with a medial upwardly extending eye, an upwardly and rearwardly inclined portion at each end of the cross bar and rearwardly extending legs extending from said laterally inclined portions and terminating in spring coils, and an upper pair of legs extending from the spring coils forward and 55 then having portions bent towards each other and into approximately abutting relationship.

2. A packing retainer for journal boxes, comprising a pair of upper parallel legs connected by a cross bar, a lower pair of parallel legs connected by a cross bar, and a spring connection between said legs, the spring connection urging the under legs apart from the upper legs, the lower legs being longer than the upper legs whereby the lower cross bar may bear against 60 the forward end of the journal box while the upper cross bar is disposed immediately in advance of the end of the journal.

3. A packing retainer for journal boxes, comprising a pair of upper parallel legs connected by a cross bar, a lower pair of parallel legs having spring connection at their rear ends with the upper pair of legs, the spring connection urging the under legs apart from the upper legs, the lower legs being longer than the upper legs 70 and at their forward ends extending downwardly

and inwardly towards each other and then extending transversely across the legs to form a cross bar, the middle of the cross bar being formed with an eye whereby the cross bar of the upper legs may be disposed immediately in front 5 of the end of a journal while the cross bar of the lower legs is disposed against the forward end of a journal box.

4. A packing retainer for journal boxes having an upper portion and a lower portion, each 10 of said portions having side legs for placement at opposite sides of a journal, means for urging the legs of the upper portion and the legs of the lower portion away from each other, the legs of the lower portion being adapted to contact from 15 above with the packing within the box and the legs of the upper portion being adapted to contact with a part within the box to resist the pressure of the bottom portion, and inwardly disposed plates extending along the legs of the 20 lower portion to substantially bridge the space between said legs and the journal.

5. A packing retainer for journal boxes having an upper portion and a lower portion, each 25 of said portions having side legs for placement at opposite sides of a journal, means for urging the legs of the upper portion and the legs of the lower portion away from each other, the legs of the lower portion being adapted to contact from above with the packing within the box and the 30 legs of the upper portion being adapted to contact with a part within the box to resist the pressure of the bottom portion, inwardly disposed plates extending along the legs of the lower portion to substantially bridge the space between 35 said legs and the journal, and means for locking the plates against swinging movement under an expansive action of the packing within the box when the plates are in their effective position. 40

6. A packing retainer for journal boxes having an upper portion and a lower portion, each 45 of said portions having side legs for placement at opposite sides of a journal, means for urging the legs of the upper portion and the legs of the lower portion away from each other, the legs of the lower portion being adapted to contact from above with the packing within the box and the 50 legs of the upper portion being adapted to contact with a part within the box to resist the pressure of the bottom portion, inwardly disposed plates extending along the legs of the lower portion to substantially bridge the space between 55 said legs and the bearing, the plates and legs of the lower portion being so constructed and assembled to allow the plates to have swinging movement about the legs, said plates having inwardly disposed extension plates to contact with the packing in advance of the journal, and coacting means carried by said extension plates 60 for locking said extension plates and the first named plates in their lowered working position.

7. A packing retainer for journal boxes having an upper portion and a lower portion, each 65 of said portions having side legs for placement at opposite sides of a journal, means for urging the legs of the upper portion and the legs of the lower portion away from each other, the legs of the lower portion being adapted to contact from above with the packing within the box and the 70 legs of the upper portion being adapted to contact with a part within the box to resist the pressure of the bottom portion, inwardly disposed plates extending along the legs of the lower portion to substantially bridge the space 75

between said legs and the journal, the plates and legs of the lower portion being so constructed and assembled to allow the plates to have swinging movement about the legs, said 5 plates having inwardly disposed extension plates to contact with the packing in advance of the journal, one of said extension plates having an opening and the other an extending locking tongue, the locking tongue of one extension plate

passing from above through the opening in the locking tongue in the second plate, the locking coaction between the extension plates being so constructed and arranged to provide means to limit the extent of upward swinging movement of said extension arms by the expansive action of the packing. 5

MARVIN H. GORMAN.
